UNITED STATES PATENT OFFICE

FINIS TALIAFERRO, OF COFFEYVILLE, KANSAS

CURTAIN ATTACHMENT

Application filed July 16, 1929. Serial No. 378,742.

This invention relates to a curtain attachment for the cabs of locomotives and has for its object to provide, in a manner as herein-after set forth, a strong, durable and thoroughly efficient attachment of the class referred to for thoroughly protecting the occupants of the cab of a locomotive from rain, snow, sleet and wind.

A further object of the invention is to provide, in a manner as hereinafter set forth, a curtain attachment capable of being readily installed with respect to the cab of a locomotive and a tender for the purpose of protecting the occupants of the cab from inclement weather.

A further object of the invention is to provide, in a manner as hereinafter set forth, a curtain attachment for the purpose referred to including a plurality of curtain members capable of being conveniently shifted to and from extended position when desired.

A further object of the invention is to provide, in a manner as hereinafter set forth, a curtain attachment for the purpose referred to including a plurality of curtain members provided with stay elements formed of a material which will not injure or hurt the occupants of the cab when contacting therewith.

A further object of the invention is to provide, in a manner as hereinafter set forth, a curtain attachment for the purpose referred to including curtain members and means for maintaining such members in extended position to protect occupants of the cab from inclement weather.

A further object of the invention is to provide, in a manner as hereinafter set forth, a curtain attachment for the purpose referred to including curtain members capable of being folded in a compact manner when the attachment is not desired for use.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications

can be resorted to which fall within the scope of the claims hereunto appended.

In the drawings wherein like reference characters denote corresponding parts throughout the several views:—

Figure 1 is a fragmentary view in side elevation of a locomotive and a tender showing the adaptation therewith of a curtain attachment in accordance with this invention.

Figure 2 is a section on line 2—2 Figure 1. 60

Figure 3 is a section on line 3—3 Figure 1.

Figure 4 is a fragmentary view in vertical section illustrating the attachment coupled with the tender.

Figure 5 is a top plan view of the body portion of the attachment.

Figure 6 is a section on line 6—6 Figure 4.

Figure 7 is a fragmentary view in vertical section of a modification of the attachment coupled with the tender.

Referring to the drawings in detail 1 denotes the cab of a locomotive and 2 a tender. The cab 1 at its rear is provided with an arcuate extension 3 at the top thereof.

The attachment includes a sectional body 75 portion referred to generally at 4 and which is adapted to be secured to and depend from the arcuate extension 3. The body portion 4 includes a central part 5 and a pair of side parts 6, 7 which are directed forwardly from 80 the central part 5.

The central part 5 is positioned within the extension 3 at the rear end thereof and has its top edge conformed to the shape of the inner face of the extension 3. The central part 5 85 depends below the bottom edges of extension 3. The central part 5 at its top is formed with forwardly directed, spaced, apertured flanges 8 through which extend holdfast devices 9 for securing said central part 5 within and 90 against the inner face of extension 3. The side parts 6, 7 are of like form, but are oppositely disposed with respect to each other. Each side part is of L-shaped form to provide a forwardly directed leg 10 and an inwardly extending leg 11 which projects from the rear end of the leg 10 and opposes the rear face of the central part 5. The height of the side parts 6, 7 is less than the height of the central part 5. The legs 11 of the side parts 100

are fixedly secured to the central part 5 by suitable holdfast devices 12. The legs 10 of the side parts 6, 7 are provided with bendable tongues or flanges 13 at the tops thereof and which are adapted to be secured, by the holdfast devices 14 to the extension 3. The top edges of the legs 10 of the side parts 6, 7 are positioned in alignment with the bottom edges of the extension 3.

Secured to the outer face of each leg 10, at the forward end thereof is a yoke-shaped, vertically disposed member 15 having its rear arm 16 of less length than its forward arm 17. The forward arms 17 of the members 15 abut against and are secured to the sides of the cab 1 as at 18. The rear arms 16 of the members 15 have their top edges flush with the top edges of the forward arms 17 of the members 15. The arms 16 and 17 of the members 15 provide a support for a purpose to be presently referred to.

Projecting rearwardly from the legs 11 of the side parts 6, 7 of the body portion 4, in proximity to the inner ends of said legs 11, are supports 19, each support 19 having anchored thereto one end of a suspension bar or rod 20 which extends through and is supported by an arm 16 of the member 15 and furthermore extends through and is connected to, as well as being supported by the other arm 17 of member 15.

The suspension bar 20 corresponds in contour to the shape of a side bar 6 or 7 and is maintained in spaced relation with respect to its associated side part by a support 19 of the arms 16, 17 of the member 15. The suspension bar 20 is positioned between the top and bottom edges of a side bar 6 or 7. The legs 10, 11 of each side part have projecting from the bottom thereof a right angularly disposed flange 21 providing a spacing means for a purpose to be hereinafter referred to. The bottom of the central part 5, between the inner ends of the legs 11 and the side parts 6, 7 is formed with a rearwardly directed flange 22 which provides a spacing means for a purpose to be referred to.

The attachment also includes a pair of flexible side curtains 23, 24 and a foldable back curtain 25. The curtains 23, 24 are of greater height than the curtain 25. Each curtain 23, 24 is foldable against itself and is of a width, when extended to oppose a portion of the part 5 to close a part of the rear of the cab. When the curtains 23, 24 are extended, the curtain 25 is adapted to have its side edges detachably connected to the rear ends of the curtains 23, 24 whereby the rear of the cab is closed. The curtain 25 can be folded upon itself or rolled up when not in use. The curtains 23, 24 are extended from the rod 20 and the curtain 25 is secured at its top to the part 5 and is adapted to depend therefrom.

Each curtain is formed of any suitable flexible material which can be employed for the

purpose intended, preferably a material which will be durable and further which is impervious to moisture. The curtains 23, 24 when in suspended position are of such length that the parts thereof employed for closing the sides of the cab at the rear depend below the floor of the cab and in this connection see Figure 1.

As each side curtain is of the same construction, but one will be described as the description of one will apply to the other. Each side curtain includes a part 26 and a part 27, the former being of greater height than the latter. The part 26 is employed for closing the side and the part 27 a portion of the rear of the opening at the rear of the cab 1. The top of the part 27 is flush with the top of the part 25. The rear end of the part 27 is provided with a hem 28 in which is secured a stay member 29 formed of resilient material, preferably rubber. The stay member 29 is of circular form in cross section. The part 26 is formed with a series of stay members 30 which are secured to the outer face thereof and arranged in spaced relation. The stay members 30 are in the form of narrow slats or strips of the desired length, but of a length less than the length of the top 26. Preferably the stay members 30 are constructed of wood. Holdfast devices 31 are employed for securing the stay members 30 in position. One of the stay members 30 is arranged at the forward end, as well as being flush with the forward end edge of the part 26. The forward stay member 30 is of less length than the other stay members.

Arranged in proximity to the top edge of the part 26 are grommets 32 which are positioned in spaced relation and secured to the part 27 in proximity to the point of joinder thereof with the part 26 and further in proximity to the top edge of part 27 is a grommet 33. Connected with the parts 26 and 27 by the grommets 32, 33 are links 34 which are slidably mounted on the bar 20. Connected to the rear end of part 27 at the rear end thereof and extended upwardly therefrom is a combined coupling and latching member 35. The links or loops 34 extend a greater distance above the top edge of the side curtains than the member 35. Each rod 20 at its rear is formed with a depending U-portion 36 in which engages the member 35 and when the side curtain is extended the member 35 coacting with the portion 36 latches the rear end of the side curtain and in this connection see Figure 2.

Secured to the part 26 of a side curtain, at the lower portion of such part are flexible stay members 37 which are enclosed in the pockets 38. The members 37 are of circular cross section and formed of rubber and are of sufficient weight to maintain the lower portion of the part 26 against the edge of the flooring at the rear of the cab and front of the tender

and in this connection see Figure 1. Secured to the inner face of the lower portion of the part 26 is an extension 40 carrying an anchoring member 41 which is constructed of any suitable material, preferably rubber and it is of yoke-shaped form. The member 41 is arranged in a pocket or hem 42 formed on the extension 40. The extension 40 seats on the flooring at the rear of the cab 1, see Figure 2 and acts in connection with the member 41 to maintain the lower portion 26 in the position as shown in Figure 1.

The curtain 25 corresponds in height to the height of the parts 27 of the side curtains and is formed near its lower end with a transversely extending hem or pocket 42' in which is arranged a stay member 43 of cylindrical cross section and preferably formed of rubber. The parts 27 and the back curtain 25 are provided with coacting means, such as snap fasteners of known form, as indicated at 44 for detachably connecting the sides of the curtain 25 to the rear ends of the side curtains, when the side curtains are in an extended position. See Figures 2 and 3. Straps 45 are carried by the part 5 and are employed for detachably maintaining the curtain 25 in rolled up position. If it be desired to fold the curtain 25, it can have its lower portion folded against its upper portion and be maintained in such position by a tie member 46 carried by the curtain 25 for extension through a grommet 47 formed at the lower end of the curtain 25.

The side curtains are also detachably connected to the tender, when such curtains are in an extended position. For this purpose the forward end of the tender 2, at each side thereof is provided with a vertically disposed slotted tube or sheath 48 and in each sheath is arranged a vertically shiftable bolt 49 provided with a pair of spaced, forwardly extending, headed latching pins 50 which extend through the slits 51 of the sheath. Sealed to each side curtain is a plate 52 provided with key-hole shaped openings 53 corresponding in number to the number of the pins 50 and said openings 53 register with openings 54 of like contour formed in the side curtains. See Figure 4. The plate 52 is provided with a handle member 55. The pins 50 are adapted to extend through the openings 53, 54 and coact with the plate 52 for detachably connecting the side curtain with the tender. The side curtain has also secured therewith a reinforcing member 46, having keyhole shaped openings 57, which register with the openings 53 and 54. The arrangement of detachably connecting the side curtain with the tender shown in Figures 4 and 6 provides for the quick coupling thereof.

When the side and back curtains are in extended position the upper portions thereof are held clear of the parts 5, 6 and 7 of the body portion 4 by the flanges 21 and 22.

The manner of connecting the side curtains with the tender does not make a solid connection, but enables the bolts 49 to work up and down carrying the side curtains therewith while the engine is in operation, and then further in case of accident, the side curtains can be quickly disconnected from the tender and enable the occupants of the cab to get out.

The stay members 29 and 43 are constructed of rubber, preferably rubber tubing, and this statement also applies to the stay members 40 so that the parties working in the cab can be protected from receiving bumps and bruises which they would receive if the stay members were constructed of metallic or other heavy material.

In the modification shown in Figure 7 for slidably and detachably connecting the side curtains to the tender, the sheath 48 and bolt 49 are dispensed with, as well as plate 52 and the key-hole shaped openings, and in lieu thereof there is employed a bracket 58 adapted to be secured to the tender 2 and formed with a vertical, tubular portion 59. A carrier 60 of U-shaped cross section overlaps and is secured by the holdfast devices 61 to part 26 of the side curtain, and which has extending therefrom an arm formed of a vertical part 62 and a horizontal part 63 which is integral with carrier 60 and offsets part 62 with respect to the latter. The part 62 is slidably and detachably mounted in the tubular portion 59. The carrier 60 has a handle piece 64.

The curtain attachment can be readily installed with respect to the tender and cab and quickly moved to protecting position, the curtains forming protecting members, and further can be expeditiously moved to open position when desired. The side curtains are detachably connected at their forward ends to the cab, by suitable means 56', which can be of any form of spring controlled snap fastening through openings in the curtains, or hooks fastening through openings in the curtains or any other desirable means for such purpose. See Figure 3. The side curtains can also be provided with tie members 57' for maintaining them in folded position. See Figure 3.

It is thought the many advantages of a curtain attachment for protecting occupants of a railway cab, such attachment being as shown can be readily understood, and although the preferred embodiment of the invention is as illustrated and described, yet it is to be understood that changes in the details of construction can be had which fall within the scope of the invention as claimed.

What I claim is:

1. A curtain attachment for locomotive cabs comprising flexible, foldable, side and back curtains, means for suspending said curtains from the top of the rear portion of the

cab at the sides and back of such rear portion, means for detachably connecting the side curtains at their forward sides to the cab forwardly of the rear end of the latter, 5 means for detachably connecting the sides of the back curtain to the rear sides of the side curtains, said side curtains of a width to have a part thereof extend at the back of the cab to close portions at the rear end 10 of the cab, and means for detachably connecting the side curtains to the tender of the locomotive.

2. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end 20 of the cab, and means for detachably connecting said rear part to said back curtain.

3. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end 25 of the cab, means for detachably connecting said rear part to said back curtain, and means for slidably and detachably connecting said side curtains to the tender of a locomotive.

4. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end 35 of the cab, means for detachably connecting said rear part to said back curtain, and extensions connected to the inner faces of said forward part for seating on the floor of the cab and provided with anchoring members.

5. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end 40 of the cab, means for detachably connecting said rear part to said back curtain, means for slidably and detachably connecting said side curtains to the tender of a locomotive, and extensions connected to the inner faces of said forward part for seating on the floor of the cab and provided with anchoring members.

6. In a curtain attachment for locomotive cabs a pair of foldable side curtains, a foldable back curtain, said curtains for suspension from the top of the rear portion of the cab, each side curtain having its forward part

of greater height than its rear part, said rear part for closing portions of the rear end of the cab, means for detachably connecting said rear part to said back curtain, spaced, vertically disposed stay members carried by said side curtains, and a transversely extending stay member carried by said back curtain.

7. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end of the cab, means for detachably connecting said rear part to said back curtain, means for slidably and detachably connecting said side curtains to the tender of a locomotive, spaced, vertically disposed stay members carried by said side curtains, and a transversely extending stay member carried by said back curtain.

8. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end of the cab, means for detachably connecting said rear part to said back curtain, extensions connected to the inner faces of said forward part for seating on the floor of the cab and provided with anchoring members, spaced, vertically disposed stay members carried by said side curtains, and a transversely extending stay member carried by said back curtain.

9. In a curtain attachment for locomotive cabs a pair of foldable side curtains, a foldable back curtain, said curtains for suspension from the top of the rear portion of the cab, each side curtain having its forward part of greater height than its rear part, said rear part for closing portions of the rear end of the cab, means for detachably connecting said rear part to said back curtain, means for slidably and detachably connecting said side curtains to the tender of a locomotive, extensions connected to the inner faces of said forward part for seating on the floor of the cab and provided with anchoring members, spaced, vertically disposed stay members carried by said side curtains, and a transversely extending stay member carried by said back curtain.

10. In a curtain attachment for locomotive cabs a pair of foldable side curtains, a foldable back curtain, means secured to the rear portion of a locomotive cab and depending from said portion for suspending said curtains, each side curtain having its forward part of greater height than its rear part, said rear part for closing portions of the rear end of the cab, means for detachably

connecting said rear part to said back curtain, means for detachably connecting said forward part to the sides of a locomotive cab, and means for slidably and detachably connecting said side curtains to the tender of the locomotive.

11. In a curtain attachment for locomotive cabs a pair of foldable side curtains, a foldable back curtain, means secured to the rear portion of a locomotive cab and depending from said portion for suspending said curtains, each side curtain having its forward part of greater height than its rear part, said rear part for closing portions of the rear end of the cab, means for detachably connecting said rear part to said back curtain, means for detachably connecting said forward part to the sides of a locomotive cab, means for slidably and detachably connecting said side curtains to the tender of the locomotive, and stay members secured to said curtains.

12. In a curtain attachment for locomotive cabs a pair of foldable side curtains, a foldable back curtain, means secured to the rear portion of a locomotive cab and depending from said portion for suspending said curtains, each side curtain having its forward part of greater height than its rear part, said rear part for closing portions of the rear end of the cab, means for detachably connecting said rear part to said back curtain, means for detachably connecting said forward part to the sides of a locomotive cab, means for slidably and detachably connecting said side curtains to the tender of the locomotive, and said side curtains and means for suspending such curtains having coacting elements for latching the side curtains in extended position.

13. In a curtain attachment for locomotive cabs a pair of foldable side curtains, a foldable back curtain, means adapted to be secured to the locomotive cab for suspending said curtains from the rear portion of said cab at the sides and back thereof, means for detachably connecting said side curtains to said back curtain, holding means for the side curtains extending therefrom and adapted to be seated upon the floor of the cab, stay members secured to said curtains, and means for slidably and detachably connecting said side curtains to the locomotive tender.

14. In a curtain attachment for locomotive cabs a pair of foldable side curtains, a foldable back curtain, means adapted to be secured to the locomotive cab for suspending said curtains from the rear portion of said cab at the sides and back thereof, means for detachably connecting said side curtains to the said back curtain, holding means for the side curtains extending therefrom and adapted to be seated upon the floor of the cab, stay members secured to said curtains, means for slidably and detachably connecting said side

curtains to the locomotive tender, means for detachably connecting said side curtains to the sides of the locomotive cab, and means for latching said side curtains in an extended position.

In testimony whereof, I affix my signature hereto.
